CHRISTIAN REINKER AND WILLIAM REINKER, OF LAKEWOOD, OHIO.

ELECTRIC CALL-BELL.

No. 905,229.

Specification of Letters Patent.

Patented Dec. 1, 1908.

Application filed April 27, 1908. Serial No. 429,509.

To all whom it may concern:

Be it known that we, CHRISTIAN REINKER and WILLIAM REINKER, citizens of the United States, residing at Lakewood, in the county of Cuyahoga and State of Ohio, have invented certain new and useful Improvements in Electric Call-Bells; and we do declare that the following is a full, clear, and exact description of the invention, which will enable others skilled in the art to which it app pertains to make and use the same.

Our invention relates to improvements in electric call bells; and the improvement consists in a construction and arrangement of parts, substantially as hereinafter shown and described and more particularly pointed out in the claims.

The general object of the invention is to provide a call bell constructed and adapted to be electrically operated from different distant stations or places to produce different tones or sounds according to the station or place selected. Another object is to provide a simplified construction in which all the operating parts are contained within and completely covered by the bell.

In the accompanying drawings, Figure 1 is a sectional view centrally through the bell and its mounting and showing the electrical connection for the bell in diagrammatic form. Fig. 2 is a sectional view on line 2—2, Fig. 1 showing the mounting alone and with the bell removed. Fig. 3 is a cross section on line 3—3, Fig. 1.

The invention as thus shown comprises a base or mounting 2 and an integral standard 9 thereon carrying electromagnets 3; an armature 4 and hammer 5, contact making and breaking members 6 and 7, respectively, and bell 8 over all. All the operating parts and the bell are mounted and secured upon said standard, the bell 8 confining and covering everything above the said base. With this end in view, standard 9 has a lateral arm 10 at about its middle to which the core piece 11 of one of the pair of the magnets 3 is fastened. The other magnet of the pair is built up around the standard itself, and said standard 9 has a transverse opening 12 above the said coils to accommodate the inner end of armature 4, which is suspended at this point above said magnets by a flat spring 13, bent or bowed upwardly at one end by which it is fastened to said standard by screw 14. Its other

end is bent or sprung upward at 6 to contact with the end of contact screw 7. Armature 4 is secured by screws or rivets to said spring 13 approximately midway between the ends of the spring, and by reason of this arrangement and location of contact screw 7, said spring serves as a spring support for the armature and also a spring contact member for electrical make and break purposes. Screw 7 is supported by two spring plates 15, one upon either side of a short projection 16 integral with standard 9 and insulated from said projection by suitable insulating material placed about the fastening screw 17 which secures said plates in place. Screw 7 has threaded engagement with both plates 15, and when screwed therein the ends of the plates are sprung apart from each other to provide a spring locking action upon the threads engaged and thereby lock the screw firmly in any adjusted position, thus dispensing with lock nuts such as usually employed to prevent disarrangement of the contact point as set. Bell 8 is removably mounted upon top of standard 9 by screw 18.

The device as described up to this point will operate to ring bell 8 in full strength by a vibratory movement of hammer 5 upon pressing push button A to close the electric circuit a in which magnets 3 are connected and as diagrammatically shown in Fig. 1. Now, in order to obtain alarms having distinctly different sounds, we provide additional means to those already described and to coöperate with the main alarm mechanism. Thus, in one instance, hammer 5 is withheld from striking bell 8 and restricted in its vibratory movement so as to impart merely a buzzing sound, and in another instance bell 8 is deadened in tone by pressing a cushioning member against it during the strokes by hammer 5. The means to this end comprise two magnet operated devices electrically connected in circuit in part with line a and each controlled by its own push button B and C, respectively. The means for producing a buzzing effect of hammer 5 consist of magnet 20 having its core piece 21 secured to standard 9 by a screw 22 and with the outer end of the core piece bent upwardly at right angles to come opposite armature 23, which is pivoted to ears on standard 9.

2
A spring 24 normally holds armature 23 in raised position, and stem 25 of hammer 5 passes through an opening 26 in the outer or free end of armature 23, and when thus raised the said stem has sufficient free play to permit hammer 5 to strike bell 8. However, when armature 23 is drawn down by the magnet, the arc movement thereof slightly limits the play of the stem 25 to prevent the hammer from striking the bell, and stem 25 is preferably disposed in an inclined relation to the armature to still further foreshorten the relative movement between the parts when the armature is attracted by magnet 20. To bring this action under adjustable control, stem 25 has a shoulder or enlargement 27, and armature 23 has a set screw 28 at its end which is adapted to engage the said shoulder when opposite thereto, as when the armature is down. Magnet 20 is energized when push button B closes the circuit over line b and which brings magnets 3— also in circuit. Thus, magnet 20 is electrically connected in parallel with magnets 3— and a shunt is provided through spring 24— and contact piece 29— to maintain a circuit for make and break operations of magnets 3— in line a. Thus the current is divided between the magnets 20— and 3—, respectively, without affecting the operation of either during the time push button B is pressed to close the circuit to operate the device as a buzzer signal or alarm.

35 Now referring to push button C— and the corresponding device for changing the ringing tone of bell 8—, we employ a small magnet 30— mounted on upright core 31— extending from base 2—, and arrange an armature 32— above the same by pivoting it on a post 33— also supported on base 2— but insulated theretrom. Armature 32— has an arm 34— at one end which is bent at an angle thereto along parallel lines with the adjacent wall of bell 8—. A felt or other cushioning strip or segment 35— is mounted at the end of arm 34— and is adapted to press against the bell and thereby deaden and change its tone when armature 32— is actuated by magnet 30—. This occurs when push button C is pressed and a circuit established over line a in part and over line c connected with magnet 30— and post 33—. When magnet 30— is energized, armature 32— is attracted and contact is made between an end part 37— on the armature and a stationary contact member 38— connected by line d to line a, thereby placing magnet 30— in parallel circuit with magnets 3— and providing a constant circuit for magnet 30— during make and break operations of magnets 3—.

Having thus described the device in its entirety, it is plainly seen that either of the

three push buttons, A, B or C, may be used to close an electrical circuit to operate the call-bell, and in each and every event, the bell hammer 5— will be vibrated to sound an alarm. However, the sounds produced will be different in tone or character dependent upon which button is selected and pressed, or to be more exact, dependent upon whether the main call magnets 3— are energized alone or in combination with either of the two auxiliary magnets 20— and 30—, respectively, which have a supplementary control of the bell hammer 5— and the bell 8—.

Various modifications of the bell and its mountings and parts may be made from that shown and described and we do not limit ourselves to the specific construction shown but reserve the right to construct and assemble the working elements in various forms and ways to the same ends and purposes as set forth herein and as embodied in the following claims.

We claim—

1. An electric call-bell and a base and standard on which the bell is mounted, and means to ring the bell, in combination with electrically operated devices adapted to coact with said means to ring the said bell and to change the sound produced thereby. 95

2. An electric call-bell and a base and standard supporting the same and an electrically controlled hammer to ring said bell, in combination with supplemental electrically operated devices adapted to change the tone of the sound produced by said hammer. 100

3. An electric call-bell and a magnetically operated hammer therefor, combined with a separate magnet and means adapted to be operatively controlled from a distance and to restrict the movement of said hammer to a buzzing sound. 105

4. An electric call-bell and a magnetically operated hammer therefor, combined with a separate magnetically controlled device adapted to limit the vibratory movement of said hammer, said device being in contacting relation with the hammer arm. 110

5. An electric call-bell having a magnetically operated hammer, in combination with an electrically operated device adapted to change the vibratory tone of said call-bell said device comprising a magnet and an armature controlled thereby and hand controlled means to close the circuit on said magnet and armature. 115

6. An electric call-bell having a hammer and magnet to operate the same, combined with a restraining device for said hammer having a magnet electrically connected in parallel with said call-bell magnet. 120

7. A call-bell having a magnetically controlled hammer, combined with an auxiliary device to restrain the movement of said hammer, a supplemental device to co-act with the 125

hammer to change the tone of the call-bell, and electrical means to operatively connect said hammer and either of said devices.

8. The combination of a main magnet and sounding member for a bell and a magnetically operated device adapted to change the striking movement of the hammer into a buzzing sound, with a magnetically operated device adapted to bear against the bell to change the sound thereof, and hand controlled means to place the hammer into direct working relationship with the bell or with either of said devices.

9. A bell and a mounting therefor comprising a standard having a through opening and magnets supported adjacent thereto, an armature opposite said magnets and located within said standard opening and a hammer on said armature, a spring member secured at one end to said standard and attached to said armature and having its opposite end bent to provide a spring contact portion, and a contact screw supported by said standard opposite said spring contact portion.

10. An electric call-bell having a hammer and an arm therefor provided with an armature and a magnet to operate the hammer through the arm, in combination with an armature adapted to engage said arm and limit the movement thereof, and a magnet to operate said armature, and means to control said magnets.

11. An electric call-bell and a hammer and arm and a magnet to operate said arm and hammer, in combination with a pivoted arm adapted to engage the call-bell to change

the sound thereof and a magnet to control said pivoted arm; and push buttons and electrical connections controlled thereby extending to both said magnets.

12. A call-bell and a magnetically operated hammer, in combination with means to muffle said hammer and separate means to deaden the sound of the bell, said means comprising a plurality of magnets and electrical connections for said magnets.

13. A call-bell and a hammer therefor and a magnet to operate the hammer, combined with a device adapted to produce different sounds in the bell, one of said devices constructed to limit the stroke of said hammer against the bell and the other to muffle the bell, separate magnets for said devices and push-button connections therefor.

14. A call-bell, a base and a standard integral therewith upon which said bell is removably secured, in combination with three different magnets within said bell supported upon said base and standard, an armature for each magnet and a hammer operatively connected with one of said armatures, means adapted to limit the stroke of said hammer connected with another of said armatures and means to deaden the sound of the bell connected with the other of said armatures.

In testimony whereof we sign this specification in the presence of two witnesses.

CHRISTIAN REINKER,
WILLIAM REINKER.
